HYDRAULIC PUMP OR MOTOR

Harry L. Chisholm, Jr., Buffalo, N. Y., assignor to
 Houdaille-Hershey Corporation, Detroit, Mich.,
 a corporation of Michigan

Application April 2, 1942, Serial No. 437,334

3 Claims. (Cl. 103—123)

My invention relates to hydraulic devices, particularly of the rotary type, which can be operated with equal efficiency to function as a pump or as a motor. The invention concerns particularly rotary hydraulic structures such as the type disclosed in Bliss Patent No. 2,271,730, dated February 3, 1942, or as disclosed in the copending application of Magrum and Chisholm, Serial No. 398,246, filed June 16, 1941. In this type of hydraulic structure, one or more rotors of generally elliptical shape define with cylinder walls crescent-shaped working chambers connectable with fluid inlets and outlets, and with blades engaging the outer surfaces of the rotors and disposed between the inlets and outlets for directing the fluid flow through the structure.

Spring means are usually provided for holding the blades against the rotors, and, in some prior art arrangements, the blades are subjected at their outer ends to the full pressure of the fluid flow, for assisting the spring means in holding the blades against the rotor. Such arrangement obviously creates undue friction between the blades and the rotors, which friction increases with the fluid pressure and will materially cut down the output efficiency of the hydraulic structure whether operating as a pump or a motor.

The important object of my invention is to more effectively and efficiently control the operation of the blades and their engagement with the rotors so that the pressure engagement of the blades with the rotors will be substantially constant under all pressures of the fluid flow through the structure and with minimum friction, but with the blades at all times intimately held against the rotors to prevent leakage. This efficient control I preferably accomplish by subjecting the blades to fluid pressure at their outer ends just sufficient to counteract the fluid pressure tending to unseat the blades, or slightly greater than the unseating pressure, so that the spring means may then function alone, or with the assistance of sufficient pressure, to hold the blades seated against the rotors with the same pressure under all conditions of flow through the structure, and with minimum friction, so as to avoid loss of energy and efficiency particularly during starting of the structure as a pump or motor.

My improved structure and control is embodied in the accompanying drawings, in which:

Figure 1 is a cross section on plane I—I of Figure 2;

Figure 2 is a section on plane II—II of Figure 1;

Figure 3 is a section on plane III—III of Figure 1;

5 Figure 4 is an enlarged side view of one of the blades, partly in section; and

Figure 5 is a section on plane V—V of Figure 4.

Briefly describing the structure shown, its housing comprises the cylindrical wall 10 having the inner end wall or head 11 integral therewith, the outer end of the housing receiving the outer end wall or head 12. Fitting into the wall 10 and seating against the head 11 is the cylindrical block 13 between which and the outer head 12 are clamped the various elements which form the pump cylinders. A drive shaft 14 extends into the housing and is journalled in ball bearings 15 and 16 supported respectively by the block 13 and the head 12, the shaft extending outwardly from the head 11 for connection with a driving source such as an electric motor when the structure is to be driven as a pump, or for connection with mechanisms to be driven when the structure is operated as a hydraulic motor. 10 A fitting 17 receives the shaft and is secured, as 20 by bolts 18, to the head 11, and may serve as a bracket for supporting the structure. The fitting 17 engages a washer 19 for compressing packing 20 around the shaft to prevent leakage. 25 The finger spring 19' is clamped at its outer periphery between the bracket 17 and the head 11, but is free therefrom inwardly to bear against the washer 19 for application of pressure on the packing, thus assuring automatic take-up 30 for wear or deflection.

35 The pump cylinder forming elements are rings and plates clamped together between the head 12 and the block 13 by a clamping ring 21 having threaded engagement in the open end of 40 the housing wall 10 and abutting the flange 22 of the head 12. As shown, there are two rings 23 and 24, an inner plate 25, an intermediate plate 26, and an outer plate 27, the outer diameter of the rings and the plates being such 45 that they will fit snugly in the cylindrical bore of the wall 10, the plates and rings being held against rotational displacement by dowel pins 60 extending therethrough and anchored in the block 13. The rings and plates define annular 50 cylindrical spaces 28 and 29 into which the rotor elements 30 and 31 extend for rotation with the shaft 14 to which they are secured as by keys 32. The rotor elements 30 and 31 are of generally 55 elliptical shape so as to define, with the cylinder space walls, crescent-shaped working chambers.

The two rotors are displaced 90° on the shaft 14, so that the opposite working chambers 33 and 34 between the rotor 30 and ring 23 will have their maximum volumetric displacement when the working chambers 35 and 36 between the rotor 31 and ring 24 have their minimum volumetric displacement.

The block 13 is cored to provide an annular suction or intake space S (Fig. 3 and dotted lines Fig. 1) which communicates with the inlet 37 on the wall 10 and is connected by suitable piping with a source of fluid such as oil. By independent coring, the block 13 has the segmental discharge space D (Fig. 3 and dot-dash lines Fig. 1) communicating with the outlet 38 on the wall 10 connectable by suitable piping with hydraulic devices for receiving fluid under pressure when the structure is operated as a pump.

For the cylinder spaces 28 and 29, in which the rotors operate, diametrically opposite fluid inlet passageways *s* and *s'* and diametrically opposite discharge passageways *d* and *d'* are provided. To form these passageways, the rings 23 and 24 have transverse bores 41 therethrough which align with the transverse bores 42 in the plates 25, 26, and 27. The inlet passageways *s* and *s'* communicate with the cylinder spaces through ports 39 and 39', and these passageways *s* and *s'* communicate through passages S' extending from the inlet space S which communicates with the inlet 37. The passageways *d* and *d'* communicate with the cylinder spaces through ports 40 and 40' and are in communication through the passages D' with the discharge space D connected with the outlet 38.

The rings 23 and 24 are each provided with diametrically opposite blades 43 and 43' for cooperating with the rotors surrounded by the rings, the blades operating in radially extending slots or chambers 44, the blades 43 being located between the inlet passageway *s* and the outlet passageway *d*, while the blades 43' are located between the inlet passageway *s'* and the outlet passageway *d'*.

For each blade a stem 45 is provided which extends through a passageway 45' in the respective rings 23 or 24, the blade having the opening or socket 46 receiving the inner end of the stem. At its outer end each stem is guided in a plug 47 on the housing frame 10, a spring 48 engaging between the plug and a collar 49 on the stem and tending to hold the stem inwardly for pressure engagement with the blade to hold it against the surface of the respective rotor.

The blade is of rectangular cross section and, as shown on Figures 1, 4, and 5, its lower end is sloped transversely to present the inclined surface 50 extending from one side of the blade to the other to provide a contact tip 51 which is transversely rounded so that the contact line of the blade with the rotor will be a short distance inwardly from the side of the blade adjacent to the tip. The blades are mounted in their guide slots 44 with their inclined end surface 50 at one side of the contact line exposed to the flow through the passageways *d* and *d'*, while the smaller area 50' at the opposite side of the contact line is exposed to the flow through the passageways *s* and *s'*, the flow through the passageways *d* and *d'* being the high pressure whether the structure is operating as a pump or a motor, while the flow through the passageways *s* and *s'* is always at lower pressure.

In order to obtain efficiency, it is very important that the blades be held with their tips in

perfect contact with the rotors so as to avoid leakage of fluid directly from the high pressure to the low pressure side, but at the same time the pressure holding the blades against the rotors should be kept constant and with minimum friction between the blades and the rotors. I preferably accomplish this by subjecting the blades to fluid pressure which will counteract the pressure against the surfaces 50 of the blades, such counteracting pressure being at all times the same per square inch as that of the pressure against the surfaces 50. As shown, the counteracting pressure is obtained by means of one or more passageways 52 through the blades through which the fluid may flow into the blade chambers 44 for engagement with the outer ends of the blades. I have shown two such passageways 52 at opposite sides of the longitudinal center line of the blade so as to balance the inertia force of the blade longitudinally thereof. While the structure is in operation, the blade is subjected at both ends to the fluid at the same pressure per square inch, and by proportioning the available pressure area on the outer end of the blade relative to the available pressure area at the surface 50 at the inner end of the blade, the pressure against the inner end tending to shift the blade outwardly may be entirely neutralized so that the spring 48 will alone function to hold the blade seated, or the counteracting pressure may be in excess of that required for neutralizing the pressure against the surface 50 so that the counteracting pressure will assist the spring 48 in keeping the blade seated. For example, the surface 50' exposed to low pressure at one side of the blade contact line could be of such area relative to the surface 50 that the area at the inner end of the blade exposed to the high pressure would be less than the area at the outer end of the blade, so that the differential fluid pressure would assist the spring in holding the blade seated. Thus, by equalizing the fluid pressure effect on the ends of the blade, or by differentiating the pressure effect the blade spring 48 may function alone, or in conjunction with fluid pressure, to control the accurate seating of the blades against the respective rotor under minimum friction at all times. Where the differential pressure assists the spring, this differential pressure will keep in step with the varying pressure in the passageways *d* and *d'* in the mechanism, and no matter to what extent this pressure increases, the differential pressure will correspond and will assist the spring in keeping the blades properly seated against the rotor. In order to keep the pressure balanced in the outer ends of adjacent blade chambers 44, such chambers may be connected together through passageway 53 provided in the intermediate plate 26.

My improved control of the blades will be equally efficient whether the structure is operated as a pump or as a hydraulic motor. When operated as a pump, the fluid will be drawn through the inlet 37 into the inlet space S in the block 13 from where it is drawn through the inlet passages *s* and *s'* into the pump chambers for discharge through the outlet passageways *d* and *d'* and outlet 38, the inner and outer ends of the blades being subjected to the discharge pressure by means of the passages 52 for cooperation of the differential pressure and the springs to hold the blades properly contacted with the rotors. When the device is to be operated as a motor, fluid under pressure is delivered thereto through the space D and the passages

d and *d'*, and the blade ends are subjected to the pressure of this fluid for operation in the control of the blade seating.

The rotors 30 and 31 have each four keyways 32' but only one or two of these keyways may be used for the keys 32, which are of the Woodruff type. The keyways which do not receive keys will act as collectors for pressure leakage past the sides of the rotors, which leakage fluid flows through vent grooves *v* and *v'* in the outer faces of the plates 25 and 27 for reception in the low pressure passageways *s* and *s'*.

I have thus produced a rotary hydraulic device of the type described in which the blades, under spring pressure and differential fluid pressure against its ends, are accurately controlled for perfect sealing contact with the rotors and with friction reduced to a minimum so that the structure may be operated with equally high efficiency as a pump or as a motor under all conditions of operation.

I do not desire to be limited to the exact construction, arrangement, and operation shown and described, as changes and modifications may be made without departing from the scope of the invention.

I claim as follows:

1. A hydraulic rotary structure of the type described comprising a housing defining a cylinder space, a rotor within said space shaped to cooperate with the cylinder space wall to define a working chamber, ports for said working chamber connected with the exterior of said housing, one of said ports adapted to receive fluid under high pressure and the other port adapted to receive fluid under low pressure, an abutment blade in the form of a rectangular plate between said ports engageable at its inner end with said rotor and extending radially outwardly relative to said rotor and in the plane of the rotor axis, said housing having a rectangular guide slot in which said blade has sliding bearing fit, said blade at its inner end having a contact edge adjacent to and parallel with one side thereof and providing the sole contact area for engaging the rotor, said blade end at one side of said edge being sloped or beveled to present an unvarying sloping surface to the pressure of the fluid flow through the high pressure port, means for subjecting the outer end of said blade to the pressure of the high pressure flow, said sloping surface being at a small acute angle with the rotor surface engaged by said edge whereby the high pressure fluid will exert against the blade a wedging action having a minimum lateral component and a maximum longitudinal component tending to shift it outwardly in said slot against the high pressure exerted inwardly against the outer end of the blade, the area of said sloping surface being so proportioned to the area at the outer end of the blade exposed to the high pressure that the pressure against the outer end may counteract to a predetermined degree the outward pressure against said surface for holding the blade seated with its contact edge against the rotor under all conditions of operation of the structure.

2. A hydraulic rotary structure of the type described comprising a housing defining a cylinder space, a rotor within said space shaped to cooperate with the cylinder space wall to define a working chamber, ports for said working chamber connected with the exterior of said housing, one of said ports adapted to receive fluid under high pressure and the other port adapted to re-

ceive fluid under low pressure, an abutment blade in the form of a rectangular plate between said ports engageable at its inner end with said rotor and extending radially outwardly relative to said rotor and in the plane of the rotor axis, said housing having a rectangular guide slot in which said blade has sliding bearing fit, said blade at its inner end having a contact edge adjacent to and parallel with one side thereof and providing the sole contact area for engaging the rotor, said blade end at one side of said edge being sloped or beveled to present an unvarying sloping surface to the pressure of the fluid flow through the high pressure port, means for subjecting the outer end of said blade to the pressure of the high pressure flow, said sloping surface being at a small acute angle with the rotor surface engaged by said edge whereby the high pressure fluid will exert against the blade a wedging action having a minimum lateral component and a maximum longitudinal component tending to shift it outwardly in said slot against the high pressure exerted inwardly against the outer end of the blade, the area of said sloping surface being so proportioned to the area at the outer end of the blade exposed to the high pressure that the pressure against the outer end may counteract to a predetermined degree the outward pressure against said surface for holding the blade seated with its contact edge against the rotor under all conditions of operation of the structure, and a spring engaging the outer end of said blade to assist in holding the blade against the rotor but functioning primarily to hold the blade to the rotor until pressure has been built up in the cylinder working chamber.

3. A hydraulic rotary structure of the type described comprising a housing defining a cylinder space, a rotor within said space of elliptical cross-section for cooperating with the cylinder space to define a working chamber, ports for said working chamber connected with the exterior of said housing, one of said ports adapted to receive fluid under high pressure and the other port adapted to receive fluid under low pressure, an abutment blade in the form of a rectangular plate between said ports engageable at its inner end against said rotor and extending radially outwardly relative to said rotor and in the plane of the rotor axis, said housing having a guide chamber in which said blade has sliding bearing fit, spring means urging said blade into contact with said rotor, means for subjecting the outer end of the blade to the pressure of the high pressure flow, said blade at its inner end having a contact edge close to the side of the blade facing the low pressure flow port and being beveled off in opposite directions from said edge to leave a comparatively small beveled surface exposed to the low pressure flow and a comparatively large bevel surface exposed to the high pressure flow, and said beveled surfaces being at a small acute angle with the rotor surface, said edge forming the sole area of contact of the blade with the rotor and being so disposed between the sides of the blade that the high pressure flow component radially outwardly against said large bevel surface on the inner end of said blade, will counteract to a predetermined degree the inward fluid pressure against the outer end of the blade so that the pressure differential may assist the spring means in holding the blade contact edge seated against the rotor with minimum friction.

HARRY L. CHISHOLM, Jr.
